(57) **CLAIM**

The ornamental design for a display tray for personal audio clamshell products, as shown and described.

DESCRIPTION

FIG 1 is a perspective view of a display tray having black vertical panels and white lettering on the front panel.

FIG. 2 is a perspective view of the display tray of FIG. 1, with four clamshell products.

FIG. 3 is a perspective view of a display tray having blue vertical panels and white lettering on the front panel; and, FIG. 4 is a perspective view of the display tray of FIG. 3, with four clamshell products.

The four clamshell products are shown in broken lines for illustrative purposes only and form no part of the claimed design. FIGS. 1 and 2 have distinctive shading to represent the color black for convenient illustration only. FIGS. 3 and 4 have distinctive hatching to represent the color blue for convenient illustration only.
